UNITED STATES PATENT OFFICE.

GEORG WEISS, OF ZEESEN, NEAR KONIGSWUSTERHAUSEN, GERMANY, ASSIGNOR, BY
MESNE ASSIGNMENTS, TO AMERICAN INVESTIGATION CORPORATION, OF NEW
YORK, N. Y., A CORPORATION OF MARYLAND.

STABILIZING SURFACE FOR AIRCRAFT.

Application filed October 31, 1922. Serial No. 598,072.

To all whom it may concern:

Be it known that I, GEORG WEISS, a citizen of the Republic of Germany (whose post address is Zeesen, near Konigswusterhausen, Germany), have invented new and useful Improvements in Stabilizing Surfaces for Aircraft, of which the following is a full, clear, concise, and exact description, reference being had to the accompanying drawings, forming a part of this specification.

Airships with stabilizing and rudder planes or surfaces which are rigid in themselves and in which staying or stiffening means are located in the interior of this structure in similar manner as in the supporting planes of flying machines, are known. Said stabilizing and rudder planes are usually held in position by stiffening means arranged outside of the hull of the ship and are, therefore, pivotally connected to the latter. Said stiffening means, however, give rise to a considerable resistance of the air.

My invention relates to a new stabilizing plane for lighter than air crafts and the main object of my invention is to remedy this defect by avoiding all and any stiffening means outside of the hull structure.

Further objects and advantages of the invention will be set forth in the detailed description.

In the accompanying drawings, Figure 1 is a side view of the stabilizing planes. Figs. 2 to 4 are cross-sections of the stabilizing planes shown in Figure 1, but varying in some details of construction within the scope of my invention. Figs. 5, 6 and 7 are detail views of the enlarged portions of a frame member. In Figure 2 the frame members *a* are diametrically inserted within the transverse girders *b* of the air craft and connected with the latter directly at the points *d* and further by means of stays *c* which preferably may be wires. Just as the connecting points *d* are pivotal points or rigid points, they act to transmit to the transverse girders *b* either compressive stresses only or compressive stresses and bending moments combined.

Figures 3 and 4 illustrate two modifications, wherein the frame members *a* are rigidly connected with the transverse girders *b*. In both cases the inner ends of the frame members *a* are enlarged in order to

better receive the bending moments. In the modification shown in Fig. 4 the enlargement of the frame members *a* is such that ample hollow spaces *e* are formed therein which may be utilized with great advantage. Thus the hollow space may be used, as shown in Figures 5, 6 and 7, to find therein accommodation for parts such as e. g. rudder controlling cables and bearings and the like, and further may be used e. g. in the lower stabilizing surface as a continuation of the gangway *f*, it being preferable in such a case to dispense with the latter in the interior of the hull above the lower stabilizing surface, whereby the advantage of a considerable decrease of weight is ensured.

Moreover the thus constructed stabilizing plane is in particular adapted for the provision of a footplate or a place *g* for steersman to stand particularly for reserve purposes. This advantage is the more important for the reason that the rudder controlling cables may be given in this case a possibly least length only whence the possibility or probability of their being rendered unserviceable or destroyed, e. g. through projectiles or in case of fracture of the framework, diminishes in accordance with the reduced length thereof. Regarding the usual reserve place for steersman to stand as hitherto arranged and provided in about one third of the length of the ship the reserve stand above suggested represents a noticeable advance in the art.

From the foregoing description it will be seen that simple and efficient means are herein provided for accomplishing the objects of my invention, but while the elements shown and described are well adapted to serve the purposes for which they are invented, it is to be understood that the invention is not limited to the precise construction set forth, but includes within its purview such changes as may be made within the scope of the appended claims.

What I claim is:

1. In a lighter than air craft, girder frame members and stabilizing planes comprising hollow tapering frame members rigidly secured to the girder frame members.
2. A lighter than air craft, comprising a body having transverse annular girder frame members, and provided with a fore and aft tunnel, and hollow stabilizing planes

comprising outwardly extended and tapering members, having their enlarged bases directly and rigidly secured to the transverse girders, one of said hollow stabilizers forming an offset extension of the tunnel.

3. A lighter than air craft, comprising a hull frame having transverse annular girder frames and a hollow stabilizer comprising downwardly projecting and tapering frame members having their enlarged bases di-

rectly and rigidly secured to the annular girders, the forward end of the stabilizer affording a free space for the pilot.

In witness whereof, I have hereunto subscribed my name in presence of two witness.

GEORG WEISS.
